RIDING TOY

Laurie J. Campbell, Raymond J. Lohr, Calvin S. Cook,
and Paul G. Goodwin, Erie, Pa., assignors to Louis
Marx & Co., Inc. (Delaware), New York, N.Y.

Filed Nov. 5, 1971, Ser. No. 196,265

Term of patent 14 years

Int. Cl. D21—01

U.S. Cl. D34—15 AJ

F/G. I

FIG. 2

FIG. 3

FIG. 1 is a front and left side perspective view of a riding toy showing our new design;

FIG. 2 is a rear elevational view thereof; and
FIG. 3 is a right side elevational view thereof.

We claim:

The ornamental design for a riding toy, as shown.
